UNITED STATES PATENT OFFICE.

MAX HARTENHEIM, OF PITTSBURGH, PENNSYLVANIA, ASSIGNOR TO STANDARD CHEMICAL COMPANY, OF PITTSBURGH, PENNSYLVANIA.

DESIGN FOR A WOVEN-GLASS SEPARATOR FOR BATTERIES.

56,923.

Specification for Design.

Patented Jan. 18, 1921.

Application filed March 30, 1920. Serial No. 370,015. Term of patent 14 years.

To all whom it may concern:

Be it known that I, MAX HARTENHEIM, a citizen of the German Republic, residing at Pittsburgh, in the county of Allegheny and State of Pennsylvania, have invented a new, original, and ornamental Design for Woven-Glass Separators for Batteries, of which the following is a specification, reference being had to the accompanying drawing, forming part thereof.

The figure is a plan view of a woven glass separator for batteries, showing my new design.

I claim:

The ornamental design for a woven glass separator for batteries, as shown.

MAX HARTENHEIM.

Witnesses:

WILLIAM GARLEY,
CHARLES LEIBSON.
